UNITED STATES PATENT OFFICE.

CHARLES G. BACON, OF BALLARD, WASHINGTON.

CAR-STAKE SOCKET WITH TRIPPING DEVICE.

No. 831,696.

Specification of Letters Patent.

Patented Sept. 25, 1906.

Application filed May 7, 1906. Serial No. 315,600.

To all whom it may concern:

Be it known that I, CHARLES G. BACON, a citizen of the United States, residing at Ballard, in the county of King, in the State of Washington, have invented a new and useful Improvement in Car-Stake Sockets with Tripping Devices, of which the following is a full, clear, and exact description.

This invention relates to railway-cars employed in the transportation of logs; and its object is the provision of improved car-stake holders adapted for use with the ordinary type of flat-cars and which is reliable in its action and conveniently manipulated to release logs for unloading without subjecting the operator to any danger from injury in being struck by the same.

The invention consists in the novel construction and combination of devices, as will be hereinafter described, and particularly pointed out in the appended claims.

In the accompanying drawings, illustrating the preferred construction of my invention, Figure 1 is an under side plan view of a railway-car with my improvements applied thereto. Fig. 2 is a side elevation of the same, and Fig. 3 is an enlarged cross-sectional view taken through the car-body.

The reference-numeral 5 designates the platform of a flat-car having in its framework longitudinal sills 6, as is usual. To these sills are rigidly secured boxes 7 by bolts 6' passing through the wing-flanges 7' thereof. The boxes are severally formed with side walls 7" and a rectangularly-shaped plate 8, forming the front and bottom-wall, respectively, 8' and 8" and which is tiltably connected to the sides by a bolt 9 passing through apertures in the latter and a tubular socket 9' at the rear of the bottom part. When the plate 8 is in its upright position, as indicated by full lines at the left-hand side of Fig. 3, it forms with the aforesaid sides a receptacle for the bottom end of the car-stake S, and the plate is thus maintained in its operative position by means of a securing-strap 12, which is permanently connected from one end to an eye 13, attached to a side of the box adjacent to its top, and carries at its other end a link 14, having a hooked end 14'. This hook is detachably engaged within a socket 15 in the under side of a block 15', provided upon the outer side of the box opposite to the eye, and has fixedly connected thereto a guard 16, serving to prevent the lateral displacement of the link and

likewise to form thererehind a housing for the upper end of a lever 17. The latter is fulerumed intermediate of its length by bolt or pin 18 to said box, and its upper arm is of such a length as to contact at its extremity with and keep said link in its locked position, while the opposite lower arm is connected to drag-bar 19, arranged transversely of the car-body and terminating within a short distance of the outer edge of the sill at the opposite side of the car. The drag-bars, one for each box, are supported in guides 20, and each bar has at the end farthest removed from its connection with its lever a shoulder 21, engageable with a hasp 22, which is fixed to a staple 23 and is secured in such engaged position by a button 24, adapted to be entered through a slot 22' of the hasp. At each side of the car and desirably journaled in bearings 25 of the respective boxes are longitudinal shafts 26, which are connected by chains 27 with the adjacent ends of the drag-bars, which are operatively connected with the plates 8 at the opposite sides of cars, and when the hasps 22 are disengaged from the shoulders 21 by giving a partial rotation to the proper shaft the chains are coincidently wrapped thereabout to effect the unlatching of the hooks and allow the tripping of the plates 8 by the lateral pressure exerted by the load of logs upon the formerly-sustained stakes. It may be said that at the places where the logs are usually discharged the rail upon the dumping side of the track is at a lower level than the other rail, thus facilitating the tripping action above mentioned, though the device will work most satisfactorily upon an even track. To turn the shafts, a handle-arm 28 is provided for each and is disposed to lie against the under side of the adjacent sills or in a bed-socket thereon provided. When the chains are loose about a shaft, the latter are severally held in such inoperative position by hasps 29 or the like securing the arm 28 and is connected by staple 30 and locking-buttons inserted through a slot 30'.

To release the stakes at either side of the car, the hasps securing the drag-bars and securing the handle of the shaft at the opposite side are first disengaged, when by winding the chains through a partial rotation of this shaft the drag-bars are actuated to disengage the stake-retaining plates.

In operation the hasps are first disengaged from the drag-bars and from the arms of the

shafts, which are connected with the locking devices of the stake-boxes, whereupon the bars of the two boxes would be drawn by turning the chains thereof about the shaft and imparting a partial turn to the latter. Should it be desired to release but one of the stakes, then the bar controlling the locking devices of that box only would, after being disengaged from its hasp, be pulled toward the operator without the intervention of the shaft.

From the foregoing it is apparent that the stakes are released by mechanism operated from the side of the car opposite thereto, that the same can be released singly or together—that is to say, those on the same side of the car—and that the apparatus is adapted to be applied to cars of ordinary construction and without the use of "bunks" or the like expedients utilized with other stake-holders and releases, therefor with which I am acquainted.

The present invention has few parts, is not liable to get out of order, is comparatively inexpensive to make, is easily installed, and the controlling portions of the locking devices are located so that they cannot be accidentally moved or otherwise affected by the load of logs held in place by the stakes.

Having described my invention, what I claim as new, and desire to secure by Letters Patent, is—

1. A car-stake holder, the combination with a box having a hinged front and bottom portion, of a strap for securing said portion in operative position, a block on the box, a hook connected to the strap and adapted to engage with the block, a lever adapted to maintain the hook in such engagement, and a drag-bar connected to the lever for operating the same.

2. A car-stake holder, comprising a box having sides and a rectangularly-bent plate forming the front and the bottom, said plate

being hinged along the rear end of its bottom part to a bolt connected to said sides, a strap connected to one of said sides, a hook carried by said strap, a lever fulcrumed intermediate its length and adapted to engage said hook and retain the same in engagement with a block provided upon the box, said block, a drag-bar connected to said lever, and devices for securing the bar in its operative position.

3. In apparatus of the class described, the combination with the platform of a railway-car and a stake, of a box for the stake, said box having two sides, a plate forming front and bottom walls hinged to the sides by a bolt passing through both of the latter, a strap connected to one of the box sides and carrying a hook-link, said link, a block upon the box for engagement with said hook-link, a lever fulcrumed to the box, a guard forming a housing for the link and the end of the lever, a drag-bar connected at one end to the lever and provided with a shoulder at the other end, a hasp for engaging with the said shoulder, and a button for securing the hasp in its engaged position with the drag-bar.

4. The combination with a car provided with a platform having sills, stake-holders comprising boxes secured to said sills and severally provided with a hinged front, locking devices for securing said fronts in operative position, connections between the said locking devices of the boxes at one side of the car with a shaft disposed upon the opposite side and arranged to disconnect said locking devices from the respective fronts, and means to prevent the accidental unlocking of the same.

In testimony whereof I affix my signature in the presence of two witnesses.

C. G. BACON.
